UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,234,773.

Specification of Letters Patent. Patented July 31, 1917.

Application filed May 26, 1916. Serial No. 100,124.

To all whom it may concern:

Be it known that I, JOHN KIEWICZ, a citizen of the United States, residing at Boston, county of Suffolk, State of Massachusetts, have invented an Improvement in Sewing-Machines, of which the following description, in connection with the accompanying drawing, is a specification, like characters on the drawing representing like parts.

This invention relates to sewing machines and particularly to sewing machines of that type in which the feed mechanism includes a rotatable feed-controlling member or feed cam, and the object of the invention is to provide an improved means for actuating the feed-controlling member by which the latter is given a varying speed in timed relation with the operation of the stitch-forming mechanism. As illustrative of sewing machines of the above type, I would refer to so-called buttonhole sewing machines that are adapted to form the edge stitches on a buttonhole. These sewing machines are commonly provided with stitch-forming mechanism and work-holding means and with a rotatable feed cam or feed-controlling element by which the stitch-forming mechanism and work-holding means are given a relative feeding movement first in one direction and then in the other thereby to effect the formation of the edge stitches down one side of and then back on the other side of the buttonhole. In some buttonhole sewing machines, this relative feeding movement is secured by moving the stitch-forming mechanism relative to the work-holding means and in other buttonhole sewing machines such relative movement is secured by moving the work-holding means relative to the stitch-forming mechanism.

An example of a buttonhole sewing machine in which the feeding movement is secured by moving the stitch-forming mechanism relative to the work-holding means is found in United States Letters Patent No. 655,637, dated August 7, 1900, and an example of the type of buttonhole sewing machine in which the work-holding means moves will be found in the United States Patent No. 1,030,589, dated June 25, 1912.

In both of the above-cited patents the

feed-controlling member or feed cam is given an intermittent movement during the stitching operation thereby giving the desired intermittent feed to the work so that when the needles are in the work, the latter will be at rest or substantially at rest, while the feeding movement of the work will occur when the needles are withdrawn from the work, and this intermittent movement is secured by means of a pawl-and-ratchet mechanism actuated from the driving shaft of the stitch-forming mechanism. One disadvantage inherent in the use of a pawl-and-ratchet mechanism for giving this intermittent movement is that when the device is operated at very high speed, the inertia of the parts may cause the ratcheted member to overrun, and if this takes place, the intermittent movements of the ratcheted member will not be absolutely uniform.

I have provided herein an improved mechanism for actuating the feed cam which is positive in its operation even at excessively high speeds, but which gives to the feed cam the desired intermittent or varying motion. I accomplish this end by positively connecting the feed-controlling member to the driving shaft for the stitch-forming mechanism by means of gearing and by providing means actuated from the driving shaft for modifying the action of the gearing so that the feed-controlling member will have the desired varying speed in timed relation with the operation of the stitch-forming mechanism.

In order to illustrate the invention I have shown it as it might be applied to buttonhole sewing machines of the type illustrated in the above-mentioned patents, but I wish to state that the invention is not limited in its use to buttonhole sewing machines of this particular type, but is capable of use more generally in sewing machines involving a rotary feed-controlling element.

In the drawings, Figure 1 is a side view partly in section of a buttonhole sewing machine having my improvements applied thereto;

Fig. 2 is a bottom plan view of Fig. 1;
Fig. 3 is a detail of one end of the driving shaft showing part of the gearing for driving the feed-controlling member;

Fig. 4 is a detail view of the worm gear which meshes with and drives the feed-controlling member;

Fig. 5 is a section on the line 5—5, Fig. 4. 5 indicates generally the frame of a buttonhole sewing machine in which the stitch-forming mechanism is operatively mounted. The stitch-forming mechanism herein shown 10 comprises the upper thread-handling mechanism in the form of an eye-pointed needle 2 which is carried by a reciprocating needle bar 3 and a lower thread-handling mechanism of the type illustrated in the above-mentioned patents and which is indicated 15 generally by 4. This stitch-forming mechanism is operated from a driving shaft 5 which is journaled in the frame 1.

The work-holding means by which the work is held is herein illustrated as a clamp 20 plate 6 on which the work is supported and movable work-clamping members 7 pivotally mounted on the clamp plate and adapted to clamp the work against the clamp plate 6. During the stitching operation the work-holding 25 means and stitch-forming mechanism are moved relative to each other, and in the construction herein shown this relative movement is secured by movement of the work-holding means on the frame 1. 30 This feeding movement is derived from a rotary feed-controlling element or feed cam 8 which is rotatably mounted on the frame 1 below the work-holding means and which has a cam groove therein in which is received 35 a projection 9 depending from a slide 10 which is connected to the work clamp 6 so that movement of the slide 10 toward the right and the left, Fig. 1, will give corresponding movement to the work-holding 40 means. The feed cam 8 is constructed to give the slide 10 this reciprocating movement. The mechanism for thus giving feeding movement to the work-holding means may be similar to that shown in the Kiewicz 45 Patent No. 1,030,589, June 25, 1912, above referred to, and hence does not need any further description herein.

I have above referred briefly to a sufficient number of essential elements of a buttonhole sewing machine to enable my invention to be understood, but have not entered 50 into a detailed description of all the elements of a sewing machine, nor the operation thereof, as these will be readily apprehended by those skilled in the art and by reference to the above-mentioned patents.

The feed cam or feed-controlling element 8 is provided on its periphery with worm gear teeth that mesh with a worm 11 on a shaft 12. During the stitching operation, 55 this shaft 12 is driven from the driving shaft 5, and means are provided for modifying the action of the worm 11 in giving rotative movement to the feed cam 8 so that

the feed cam has an intermittent or substantially-intermittent movement. In accordance with my present invention this is accomplished by reciprocating the worm 11 axially of the shaft 12, as said worm is rotating. The movement of the worm 11 longitudinally of the shaft 12 in one direction during the rotation of the shaft will act to speed up or augment the action of the worm in giving rotative movement to the feed cam 8, while movement of the worm in the opposite direction on the shaft 12 will retard or nullify the effect of the worm 11 on the feed cam 8. Means are provided for thus vibrating the worm 11 in timed relation with the operation of the shaft 5, the movement of the worm in a direction to augment the rotative movement of the feed cam 7 taking place when the needle is withdrawn from the work, and the movement of the worm in the opposite direction by which the rotative movement of the feed cam 8 is nullified or retarded taking place when the needle is in the work. The worm 11 is splined to the shaft 12, this being accomplished by providing said worm with a slotted hub 13 and by providing the shaft 12 with roller projections 14 operating in the slots 13. The worm 11 is rotated from a bevel gear 15 which is geared to a bevel gear 16 fast on a shaft 17 that extends up through the bed plate of the machine and is journaled at its upper ends in a bearing 18 secured to the frame 1. This shaft 17 has a worm gear 19 on its upper end which meshes with and is driven by a worm 20 fast on the driving shaft 5. The worm 11 is thus driven positively from the shaft 5 by means of gearing. The reciprocating movement of the worm 11 is secured by mechanism separate from the above-named gearing but actuated from the 105 shaft 5. The gear 11 is provided with a grooved hub 21 in the groove of which is received projections 22 on the forked end 23 of a lever 24 pivoted at 25 to a suitable bearing 26. This elbow-lever 25 has a link 56 110 pivotally connected thereto, said link extending up through the bed of the machine and having at its upper end an eccentric strap 27 which encircles an eccentric 28 fast on the shaft 5. By this means the gear 11 will be given a complete to-and-fro reciprocation at each rotation of the shaft 5. Each rotation of the shaft 5 also gives the needle 2 a complete to-and-fro reciprocation and the gear 11 is thus reciprocated in 115 timed relation with the stitch-forming mechanism. The eccentric 27 is so positioned that the movement of the gear 11 in a direction to speed up the feed cam 8 occurs while the needle 2 is withdrawn from the work, as shown in Fig. 1, and the movement of the worm 11 in a direction to retard or nullify the rotative movement of 120 125

the feed cam 8 occurs when the needle is in the work. I will preferably so arrange the parts that the latter movement of the worm 11 will completely nullify the rotative movement of the feed cam due to the rotation of the worm 11 so that the feed cam will have an intermittent movement, but the extent to which the movement of the feed cam is varied depends upon the extent of reciprocating movement of the worm 11, and this can be varied to suit the requirements of use. It will thus be seen that the driving means for the feed cam 8 is a positive one and that the variations in the speed of the feed cam due to the reciprocation of the worm 11 are uniform. The result will be absolute uniformity in the spacing of the stitches even when the machine is running at an extremely high speed.

In buttonhole sewing machines of the type illustrated herein and in the above-mentioned patents, the shaft 5 and the stitch-forming mechanism are automatically brought to rest when the stitching on a buttonhole has been completed, and after the stitch-forming mechanism has thus been brought to rest, the feed cam 8 continues its movement to carry the work from stitching position to buttonhole-cutting position. The entire mechanism is brought to rest when the work is in buttonhole-cutting position. When the sewing machine is started again, the buttonhole is first cut and then the feed cam operates to carry the work from buttonhole-cutting to buttonhole-stitching position, at which time the shaft 5 is automatically set in operation and the stitch-forming mechanism is actuated to concatenate the edge stitches on the buttonhole. The movement of the feed cam which carries the work from stitching to buttonhole-cutting position and vice versa is derived from the driving mechanism acting directly on the shaft 12. The movement of the feed cam 8 by which feeding movement is given to the work during the stitching operation is, however, derived from the shaft 5, as above described, said shaft being driven from a driving pulley 29 which is clutched to or unclutched from the shaft by mechanism such as illustrated in said patents and which it is not necessary to describe herein. In order to provide for thus operating the worm 11 when the shaft 5 is at rest for the purpose of carrying the work from stitching to buttonhole-cutting position or vice versa, I have shown the bevel gear 15 as loosely mounted on the shaft 12 and as provided with a spring-pressed pawl 30 coöperating with the ratchet wheel 31 fast on the shaft 12. This pawl-and-ratchet is so constructed that the rotation of the gear 15 derived from the shaft 5 will be communicated to the shaft 12 through the pawl-and-ratchet 30 and 31. When the shaft 5 and consequently the gear 15 is at rest, however, the shaft 12 may still be turned to give further movement to the cam 8, the pawl 30 at this time clicking over the ratchet 31. The shaft 12 has a continuously-rotating driving pulley 32 loosely mounted thereon which is adapted to be clutched to the shaft by a suitable clutch such as shown in the above-mentioned patents and including a clutch-operating arm 33. This arm carries a projection 34 which engages a disk 35 loosely mounted on the shaft 12, the position of which is controlled by a lever 36. When the lever 36 is in the position shown in Fig. 2, the clutch for the pulley 32 is released so that said pulley will rotate freely. When the lever 36 is moved toward the pulley 32 the latter will be clutched to the shaft 12 and will positively drive said shaft. This movement of the lever 36 is controlled by the stop motion for the shaft 5 so that when the shaft 5 is brought to rest, the lever 36 will be operated to clutch the pulley 32 to the shaft 12, all as set forth in the above-mentioned patents.

When the sewing machine is started in operation, the pulley 32 is clutched to the shaft 12 and the feed cam 8 will be operated directly from the driving pulley 32 until the work is brought from buttonhole-cutting into buttonhole-stitching position. At this time the pulley 32 is unclutched from the shaft 12 and the driving pulley 29 is clutched to the shaft 5 thereby setting the stitch-forming mechanism in operation. As soon as the shaft 5 is thus operated, the feed cam will be rotated from the shaft 5, as above set forth. I have illustrated herein means operated from the feed cam 8 for thus unclutching the driving pulley 32 from the shaft 12 when the parts are brought into stitching position. This is herein accomplished by a cam projection 71 on the feed cam 8 which is adapted to engage a roll 72 on a lever 38 pivoted at 73 to the frame. This lever has pivoted thereto one end of a link 37, the other end of which is pivoted to the lever 36. The cam projection 71 is so located on the feed cam as to act on the roll 72 just when the work is brought into stitching position and at the time that the shaft 5 is set in operation. I have also herein shown means acting on the link 37 for locking the clutch for the pulley 32 disengaged during the stitching operation. This means is in the form of a finger 39 carried by the link 37 and adapted to engage a locking latch 40, as shown in Fig. 2. This latch 40 is pivotally mounted to a bracket 41 on the underside of the bed, and one end thereof is acted on by a coiled spring 42 which tends normally to hold it in its operative position. The stop motion for the shaft 5,

which is not herein shown as it forms no part of the present invention, includes a rock-shaft 43 having an arm 44 to which is connected a push-pin 45. When the stop motion for the shaft 5 is set in operation to stop the shaft and thus stop the stitch-forming mechanism at the end of a stitching operation on a buttonhole, the push-pin 45 is forced downwardly against the latch 40 10 and the latter is thus disengaged from the nose 39 thereby unlocking the lever 36 and permitting said lever to clutch the pulley 32 to the shaft 12. The shaft is then positively driven from the pulley 32 thereby to move the feed cam 8 sufficiently to carry the work from stitching to buttonhole-cutting position, after which the entire mechanism is brought to rest. During the time that the feed cam is driven directly from the 20 pulley 32, the gear 15 is stationary, but the pawl-and-ratchet 31 will permit rotation of the shaft 12. Since the mechanism for vibrating the worm 11 is actuated from the shaft 5, it will be obvious that said mechanism is inoperative when the shaft 5 is at rest and, therefore, during the time that the shaft 12 is rotated directly from the pulley 32, the movement which is given to the feed cam 8 will be a uniform motion instead of a 25 varying one.

The bevel gear 16 is splined to the shaft 17 and is held in position thereon and in mesh with the gear 15 by a roll 60 which engages the back side of the gear 16 and is carried by a rod 57 which in turn is mounted in bearings 58, 59. This rod 57 is provided with a roller projection 61 engaging the back side of the gear 15. These roller projections 60 and 61 hold the bevel gears 15 and 40 16 properly in mesh with each other. The rod 57 is held in its adjusted position by a clamping screw 63 which screws into the rod and operates in the slot 64 in the bearing 59.

This construction has the advantage that 45 it permits the gears 15, 16 to be readily changed, thus providing for changing the length or spacing of the stitches.

While I have herein illustrated a selected embodiment of my invention, I do not wish 50 to be limited to the constructional features shown.

I claim:

1. In a sewing machine, the combination with stitch-forming mechanism, of a driving 55 shaft by which said mechanism is operated, work-holding means, a feed cam for giving a relative feeding movement between the stitch-forming mechanism and work-holding means, gearing connecting said feed cam to 60 said driving shaft, said gearing including a worm gear and a worm meshing therewith, and means to reciprocate the worm in the direction of its axis in timed relation with the operation of the stitch-forming mecha-

nism whereby the feed cam is given a varying 65 movement.

2. In a sewing machine, the combination with stitch-forming mechanism, of a driving shaft by which said mechanism is operated, work-holding means, a feed cam for giving 70 a relative feeding movement between the stitch-forming mechanism and work-holding means, gearing connecting said feed cam to said driving shaft, said gearing including a worm gear and a worm meshing therewith, and means operated by the driving shaft to reciprocate the worm in the direction of its axis in timed relation with the operation of the stitch-forming mechanism whereby the 75 feed cam is given a varying movement. 80

3. In a sewing machine, the combination with stitch-forming mechanism, of a driving shaft by which said mechanism is operated, work-holding means, a feed cam for giving 85 feeding movement to the work-holding means during the operation of the stitch-forming mechanism, gearing connecting said feed cam to said driving shaft, said gearing including a worm gear and a worm meshing therewith, and means to reciprocate the 90 worm in the direction of its axis in timed relation with the operation of the stitch-forming mechanism. 95

4. In a sewing machine, the combination with stitch-forming mechanism, of a driving shaft by which said mechanism is operated, work-holding means, a feed cam for giving 100 feeding movement to the work-holding means during the operation of the stitch-forming mechanism, gearing connecting said feed cam to said driving shaft, said gearing including a worm gear and a worm meshing therewith, and means operated by the driving shaft to reciprocate the worm in the direction of its axis in timed relation with the 105 operation of the stitch-forming mechanism. 110

5. In a sewing machine, the combination with stitch-forming mechanism, of a driving shaft by which said mechanism is operated, work-holding means, a feed cam for moving 115 the stitch-forming mechanism and work-holding means relative to each other, gearing by which said feed cam derives movement from said driving shaft, and means separate from the gearing and operated from the driving shaft to augment and retard the action of the gearing in giving movement to the feed cam in timed relation with the stitch-forming movements of the stitch-forming mechanism. 120

6. In a sewing machine, the combination with stitch-forming mechanism, of a driving shaft by which said mechanism is operated, work-holding means, a feed cam for moving 125 the stitch-forming mechanism and work-holding means relative to each other, gearing connecting said feed cam to said driving shaft, and means separate from the gearing

and operated from the driving shaft to nullify and augment the action of said gearing in giving movement to the feed cam in timed relation with the stitch-forming movements of the stitch-forming mechanism.

7. In a sewing machine, the combination with stitch-forming mechanism, of a driving shaft by which said mechanism is operated, work-holding means, a feed cam for giving 10 said work-holding means a feeding movement, gearing connecting said driving shaft and feed cam, and means separate from said gearing and operated from the driving shaft to augment and retard the action of said 15 gearing in giving movement to the feed cam in timed relation with the stitch-forming movements of the stitch-forming mechanism.

8. In a sewing machine, the combination 20 with stitch-forming mechanism including a needle, of a driving shaft by which said mechanism is operated, work-holding means, a feed cam for moving the stitch-forming mechanism and work-holding means relative 25 to each other, gearing operated from the driving shaft and by which the feed cam is actuated, and means separate from the gearing and operated from the driving shaft to augment the action of the gearing when the 30 needle is withdrawn from the work and to retard the action of the gearing when the needle is in the work.

9. In a sewing machine, the combination 35 with stitch-forming mechanism including a reciprocating needle, of a driving shaft by which said mechanism is operated, work-holding means, a feed cam for giving a relative feeding movement between the stitch-forming mechanism and work-holding 40 means, gearing connecting said feed cam to said driving shaft, said gearing including a worm gear and a worm meshing therewith, and means to reciprocate the worm gear in the direction of its axis in timed relation 45 with the reciprocating movements of the needle.

10. In a sewing machine, the combination 50 with stitch-forming mechanism including a reciprocating needle, of a driving shaft by which said mechanism is operated, work-holding means, a feed cam for giving a relative feeding movement between the stitch-forming mechanism and work-holding 55 means, gearing connecting said feed cam to said driving shaft, said gearing including a worm gear and a worm meshing therewith, and means to move the worm axially in a direction to augment its rotative effect upon the worm gear when the needle is withdrawn from the work and to move said worm in the opposite direction when the needle is in the work.

11. In a sewing machine, the combination 60 with stitch-forming mechanism, of a

driving shaft by which said mechanism is 65 operated, work-holding means, a feed cam for giving a relative feeding movement between the stitch-forming mechanism and work-holding means, operative driving connections between said shaft and feed cam including 70 a worm gear and a worm meshing therewith, and means to reciprocate the worm in the direction of its axis in timed relation with the operation of the stitch-forming mechanism. 75

12. In a sewing machine, the combination with stitch-forming mechanism, of work-holding means, a feed cam for moving the stitch-forming mechanism and work-holding means relative to each other, means for 80 driving the feed cam including a worm gear and a worm meshing therewith, and means to reciprocate the worm in the direction of its axis in timed relation with the operation of the stitch-forming mechanism. 85

13. In a sewing machine, the combination with stitch-forming mechanism, of work-holding means, a feed cam for moving the stitch-forming mechanism and work-holding means relative to each other, gearing for 90 operating said cam, means for actuating the gearing and means to augment and retard the action of the gearing in giving movement to the feed cam in timed relation with the stitch-forming movements of the stitch- 95 forming mechanism.

14. In a sewing machine, the combination with stitch-forming mechanism, of work-holding means, a feed cam for producing 100 relative movement between said stitch-forming mechanism and work-holding means, means including a worm gear and worm meshing therewith for operating said feed cam, and means to reciprocate the worm in the direction of its axis in timed relation 105 with the operation of the stitch-forming mechanism.

15. In a sewing machine, the combination with stitch-forming mechanism, of work-holding means, and means for moving said 110 stitch-forming mechanism and work-holding means relative to each other, said means including a worm gear, a worm meshing therewith, and means to reciprocate the worm in the direction of its axis of rotation in timed 115 relation with the operation of the stitch-forming mechanism.

16. In a sewing machine, the combination with stitch-forming mechanism, of work-holding means, a driving shaft, gearing actuated by said driving shaft for producing a relative movement between the stitch-forming mechanism and work-holding means, and means separate from said gearing to augment and retard in timed relation with 120 the stitch-forming movements of the stitch-forming mechanism the action of said gearing in producing such relative movement. 125

6
17. In a sewing machine, the combination with stitch-forming mechanism, of work-holding means, a driving shaft, means actuated thereby for moving the work-holding means and stitch-forming mechanism relative to each other, and devices separate from said means for augmenting and re-

tarding in timed relation with the stitch-forming movements of the stitch-forming mechanism the action of such means in producing such relative movement. 10

In testimony whereof, I have signed my name to this specification.

JOHN KIEWICZ.
